PRECISION ROAD GRADER

Noel S. Iverson, New Ulm, Minn., assignor to New Ulm Manufacturing Company, New Ulm, Minn., a corporation of Minnesota

Filed July 11, 1966, Ser. No. 3,038

Term of patent 14 years

(Cl. D14—3)

FIG. 6

FIG. 1 is a view in top plan of a precision road grader showing my new design;

FIG. 2 is a view in bottom plan thereof;

FIG. 3 is a view in side elevation thereof;

FIG. 4 is a view in front elevation thereof;

FIG. 5 is a side elevational view thereof showing the side opposite that shown in FIG. 3; and

FIG. 6 is a view in rear elevation thereof.

I claim:

The ornamental design for a precision road grader, substantially as shown.
